SHIPPING CARTON

Harry Smith, Whittier, Calif.

Application January 11, 1955, Serial No. 481,169

1 Claim. (Cl. 206—46)

The present invention relates to shipping cartons in general and particularly to cartons for shipping heavy rigid tools such as pneumatically actuated trench diggers or paving breakers. More specifically, the invention comprises a new and improved shipping carton for rigid heavy tools in which use is made of the strength and rigidity of the tool itself to maintain the shape of the shipping carton which can include a container of relatively light inexpensive material such as corrugated cardboard conventionally viewed as inadequate for such use.

Goods shipped from one point to another must, if they are valuable, be packed and crated for their own protection and for the protection of other goods in transit. This is true whether the goods comprise light relatively fragile devices such as kitchen or home appliances, or whether they comprise rigid, strong and relatively heavy tools such as pneumatically actuated trench diggers. As a matter of fact, the latter devices are usually the most costly to crate for, because of their mass and value, they are boxed in wooden crates or boxes the cost of which, in the aggregate of many shipments, becomes an item of importance.

In the case of a pneumatically actuated trench digger, for example, a typical tool would be about four feet in length, eighteen inches across the handle, and could weigh approximately 35 or 49 pounds. The tool is relatively long, narrow, heavy and awkward, and its shape includes extremities which can readily pierce a thin protective enclosing casing or container unless the latter is strong and designed to receive just such contact. As a result tools of this type are conventionally boxed in individual wood shipping crates each of which includes a strong, rigid container having a removable cover or side. The container itself provides the rigidity and strength necessary to protect the tool which is suitably positioned therein and fixedly secured in place to prevent its being jostled about. Cardboard, paper and other relatively light and cheap materials have been considered as unsuitable for containers to be used in the shipping of such tools as lacking the requisite strength and also the ability to withstand the damaging blows which could be received from the tool itself as a result of the jostling and bumps inevitably encountered in shipping.

The shipping carton construction in accordance with the present invention does successfully make use of a light frangible enclosing container heretofore viewed as unsuitable and undesirable. The use of such container is made possible because each tool is securely positioned in and gives rigidity and strength to an enclosing frame which closely fits within and conforms to the interior dimensions of the container. The container, lacking in itself the strength and rigidity to support and protect the tool in the conventional manner, becomes in effect a skin dependent upon the enclosed frame and tool for its own rigidity and strength.

With an understanding of the problems characteristic of shipping tools and the like, and of the requisites of ade-

quate strength, protection, and minimum costs, it is an object of the present invention to provide a new and improved shipping carton particularly adapted for the individual packaging and shipping of heavy, rigid tools.

- 5 Another object of the invention is to provide a shipping
6 carton in which an enclosing casing is reinforced by a
7 framework employing the strength of the tool it encloses
8 for its own rigidity.

9 Another object of the invention is to provide a new and
10 improved shipping carton for rigid elongated metal tools
11 of relatively great weight in which a relatively fragile
12 exterior container is reinforced around its marginal edges
13 by a rigid frame which is itself fixed to the tool and ac-
14quires its strength and rigidity from the tool.

15 These and more specific objects will appear upon read-
16 ing the following specification and claim and upon con-
17 sidering in connection therewith the attached drawings to
18 which they relate.

19 Referring now to the drawings in which a preferred em-
20 bodiment of the invention is illustrated:

21 Figure 1 is a view in perspective of the frame in which
22 a rigid, heavy tool, such as a pneumatically actuated
23 trench digger or paving breaker, is adapted to be posi-
24 tioned;

25 Figure 2 is a side view with certain parts broken away
26 of the frame of Figure 1 with a tool positioned therein;

27 Figure 3 is a side view of the tool and frame assembly
28 secured by an encircling tensioning strap and positioned
29 within an enclosing container, the manner of assembly
30 being illustrated in dotted lines; and

31 Figure 4 is a vertical section upon the line 4—4 of
Figure 3.

32 Referring again to the drawings, a pneumatic tool com-
33 monly known as a trench digger is indicated generally by
34 the reference character 10. The exact construction,
35 dimensions, and operating characteristics of tool 10 are
36 not a part of the present invention, but certain of the
37 parts of the tool will be identified for purposes of ref-
38 erence, it being understood that instead of a trench digger
39 a paving breaker, or any other rigid, heavy, relatively
40 flat, elongated tool, could be substituted. The tool 10
41 as illustrated comprises a backhead 11 from the sides
42 of which extend hand grips 12 forming a handle over the
43 top of which extends a throttle lever 13. A hollow col-
44 umn extends downwardly from backhead 11 and may be
45 viewed as a part of the handle together with the grips 12.
46 A valve chest 16 containing an unshown cycling valve is
47 positioned at the lower end of column 14 adjacent a cylin-
48 der 17 in which is positioned a reciprocating air actuated
49 piston adapted to reciprocate at high speed and with great
50 force under the actuation of air under pressure received
51 from a source suitably connected to the tool. The blows
52 delivered by the unshown piston are transmitted to an
53 unshown spade, pick or chisel the end of which extends
54 upwardly into the frontthead 18 to be retained against dis-
55 placement by means of the steel retainer 19.

56 Considering the tool 10 as an entity it is seen to be a
57 narrow, elongated element, rigid, relatively small at its
58 working end 21, with relatively small extremities 22 at
59 the opposite end of its handle grips 12. Assuming that
60 the weight of the tool is within the range of 35-50 pounds
61 it is clear that upon being bumped, dropped, or rapidly
62 accelerated, considerable force could be exerted at one or
63 more of the extremities 21 and 22.

Referring now to Figures 1 and 2 in particular the skeleton frame in which the tool 10 is to be positioned is illustrated and indicated generally by the reference character 25. Frame 25, which in a preferred form is entirely of wood, comprises straight flat side members 26 between the extremities of which extend members 27 and 28 which will be designated as the top and bottom end

members, respectively. Bottom end member 28 has affixed to its inner surface a centrally positioned flat piece 29 formed centrally with a circular recess 31 sized closely to enclose the end 21 of tool 10. Member 29 may be of the same stock as the side and bottom walls and is secured to bottom wall 28 by means of a plurality of nails or screws, preferably the latter, indicated by the reference character 32.

At the inner corners of the frame formed by the junction of the side walls 26 and the top wall 27 there are inserted corner members 32 which extend the width of the frame and have an extension toward each other such that the space between them is equal to the width of the tool handle. These members 32 abut the extremities of the handle grips 12, as is clearly illustrated in Figure 2. To retain the handle in its mid-position in frame 25 when the lower end 21 of the tool is positioned in its seat 31 an abutment member 33 is secured to the underside of top member 27 and extends along the side of the tool handle in contact with backhead 11. A second abutment member identical to the first is provided upon the opposite side of the backhead 11 and is adapted to be positioned after the tool 10 has been placed in the frame with its end 21 seated in the seat 31 and with its handle extended between the corner members 32 and in contact with fixed abutment 33. Abutment 34 may be secured in place by nails or screws 36 to the inner face of the top wall 27 and when so positioned cooperates with member 33 to prevent any lateral displacement of the tool handle.

With the tool 10 positioned within the frame 25 and the abutment 34 in place a tensioning strap 39 of a common well known type is positioned around the tool overlapping the top and bottom walls 27 and 28 in the manner illustrated in Figure 3. Strap 39 is drawn taut and then has its opposite ends clamped together by a securing clamp member 41. The exact manner in which the strap 39 is positioned and clamped is not of the essence of this invention and the tightening operation may be performed in any suitable manner so long as it accomplishes the result of drawing the top and bottom walls 27 and 28 hard against the opposite ends of the tool 10. With the frame so clamped to the tool it is apparent that relatively longitudinal displacement of the tool and frame in the direction of the length of the side members 26 is prevented. Lateral displacement in the direction of the length of the end members 27 and 28 is also made impossible by the abutting contact of the tool with the seat 31 at one end and with the corner members 32 and the side abutment members 33 and 34 at the opposite end. The frame is rigid with and partakes of the rigidity of the tool 10.

The frame 25 and the tool 10 after being assembled are adapted to be slid into the open end of an enclosing casing or container the interior dimensions of which conform exactly to the exterior dimensions of frame 25. The container is indicated generally by the reference character 45 and is seen to include opposed end walls 46 which lie adjacent the outer faces of the frame side walls 26, side walls 47 which extend between its own end walls 46 and top and bottom walls 49 formed by folding inwardly and securing, as by adhesive, flaps 51 and 52 comprising extensions of the walls 46 and 47, respectively. Flaps 51 and 52 at the upper end of the casing or container are held in open position, as shown in Figure 3 in dotted lines,

while the tool and frame assembly are being slid into the container. But when the frame and tool are completely within the casing the flaps are folded inwardly into overlapping relationship, in the manner of the bottom wall, and are secured by suitable adhesive means to form a closed packaged unit. The container 45 snugly encloses the frame 25 which in turn is in intimate contact with and tightly drawn to the rigid tool 10 forming a compact, rigid unitary construction in which relative movement between the tool and the frame, or between either or both of those parts and the enclosing casing is impossible, and the fact that the enclosing casing 45 is relatively weak and frangible becomes unimportant.

While the particular apparatus herein shown and disclosed in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claim.

I claim:

A composite shipping carton having a frame formed of wood and a part formed of flexible paper-like material 25 providing a protective covering casing for said frame, said carton being adapted to enclose and protect a heavy T-shaped pneumatic power tool having an elongated main body and a pair of rigid hand grips projecting laterally from one end thereof, and said carton being further adapted to make use of the strength of the body of the power tool to reinforce and strengthen the same; said carton comprising a rectangular frame of wood snugly encircling said tool in the plane of said hand grips, a plurality of abutment elements secured to the opposite interior ends of said frame in positions closely against the adjacent sides of a pneumatic power tool positioned centrally of said frame, said abutment elements being adapted to hold said tool against movement relative to said frame, a high-strength band encircling said frame along the open sides 30 thereof in a plane intersecting the main body of said tool, said band being tensioned to clamp the opposite ends of said frame rigidly against the ends of said power tool thereby utilizing said main body of said tool to reinforce said wooden frame, and a casing of flexible paper-like material having a closable end and an interior dimensioned to receive said frame with a snug sliding fit, said casing providing a continuous protective covering for said frame and its contents.
